(57) **CLAIM**

The ornamental design for a conductor's podium as shown and described.

DESCRIPTION

FIG. 1 is a top, front, right elevational view of the conductor's podium;

FIG. 2 is a right side view of the conductor's podium;

FIG. 3 is a left side view of the conductor's podium;

FIG. 4 is a back view of the conductor's podium;

FIG. 5 is a front view of the conductor's podium;

FIG. 6 is a top plan view of the conductor's podium;

FIG. 7 is a bottom plan view of the conductor's podium;

FIG. 8 is a top, back, left elevational view of the conductor's podium; and,

FIG. 9 is a bottom, back, left elevational view of the conductor's podium.

The broken lines in FIG. 7 illustrate portions of the article that form no part of the claimed design. All other broken lines illustrate environmental structure and form no part of the claimed design.

1 Claim, 9 Drawing Sheets
